UNITED STATES PATENT OFFICE.

CHARLES M. CROOK, OF BRISTOL, CONNECTICUT, ASSIGNOR, BY MESNE ASSIGNMENTS, TO NATIONAL SELF-WINDING CLOCK COMPANY, OF JERSEY CITY, NEW JERSEY, AND BRISTOL, CONNECTICUT, A CORPORATION OF NEW JERSEY.

ELECTRIC CLOCK.

SPECIFICATION forming part of Letters Patent No. 711,944, dated October 28, 1902.

Application filed September 30, 1901. Serial No. 77,005. (No model.)

To all whom it may concern:

Be it known that I, CHARLES M. CROOK, a citizen of the United States of America, and a resident of Bristol, Connecticut, have invented certain new and useful Improvements 5 in Synchronizing-Clocks, of which the following is a specification, reference being had to the accompanying drawings, forming a part thereof.

10 The purpose of this invention is to provide an improved synchronizing device and to overcome certain difficulties which are encountered in synchronizing-clocks, in which the staffs of the several hands to be set are driven in a train by which they are positively connected—that is, not yieldingly connected—so that one synchronizing action sets all the hands. It will be apparent that if the 15 hands are not rigid with their respective staffs they are liable at the synchronizing action to be carried by the momentum of that action past the points, respectively, to which they are positively carried by the rotation of their staffs, slipping at the frictional connection with said staffs, and it will be apparent, 20 on the other hand, that if they are rigidly and positively connected with their staffs all the wheels of the train comprising and connecting said staffs and the shaft or gear which 25 is primarily acted upon in the synchronizing action sustain a necessary relation which cannot be altered without defeating the proper setting of the hands—that is, the several wheels of the train must be so meshed that the 30 hands shall each and all be brought to proper position on their respective dials by the rotation of the wheel or staff, which is primarily acted and rotated to a certain invariable position by the synchronizing stroke; but if 35 the hands are rigidly and unchangeably attached to their staffs, respectively, then whenever the clock is taken apart for repairs or 40 cleaning it must be reassembled with the wheels respectively meshing at the same cogs as when first assembled—that is, there will 45 be only one proper mesh—and any change in that respect will throw one or another of the hands into inconsistent position. This would necessitate marking each wheel to denote the 50 proper teeth to be meshed, and any disregard

for such marking would cause the hands to come to disagreeing positions when the synchronizing stroke is made. This would make the matter of ordinary repairs and cleaning expensive and would practically necessitate 55 for that otherwise-simple work the employment of an expert familiar with the particular clock-movement.

This invention consists in the improved synchronizing device set out in the claims 60 and in the device also set out therein for overcoming the above-mentioned difficulty by making it possible to assemble the train in any manner—that is, causing the wheels to mesh as they may chance—and yet bring the 65 hands to agreed positions.

In the drawings, Figure 1 is a front elevation of a portion of a clock-movement embodying my improvements, the frame and part of the train being cut away to disclose the 70 more essential parts of the structure. Fig. 2 is a section at the line 2 2 on Fig. 1. Fig. 3 is a detail elevation, partly sectional, of the synchronizing device, section being made at the line 3 3 on the Fig. 2. Fig. 4 is a detail section 75 axial with respect to the minute-hand staff, showing hand securing and adjusting means. Fig. 5 is a detail section at the line 5 5 on Fig. 4. Fig. 6 is a detail section at the line 6 6 on Fig. 4. Fig. 7 is a detail section 80 axial with respect to the seconds-hand staff and pinion, showing connection of said shaft with the escape-wheel shaft and the means of adjustment. Fig. 8 is a section at the line 8 8 on Fig. 6. Fig. 9 is a detail section in the 85 plane of the axis of the shaft operated upon for synchronizing, cutting through the stud or crank-wrist on which the synchronizing-lever acts and adjacent parts.

A is the front plate, and A' the rear plate, 90 of the frame.

B is the prime wheel of the train, b being the main shaft, on which said wheel is rigid, said main shaft being also the minute-hand staff. The motor connections are not shown, 95 not being a part of this invention. The escape-wheel shaft (seen at d) is in line with and at its forward end obtains bearing in the rear end of the seconds-hand staff d', and there is one shaft only, c, intermediate the 100

main shaft b and the seconds-hand staff d' , and the train from the prime wheel to the seconds-hand staff comprises the pinion C on the intermediate shaft c , the gear C' , rigidly 5 connected with said pinion by the crank-wrist or eccentric post c^2 , on which is the antifriction-roll C^2 , and the seconds-hand pinion D , rigid with the staff d' , which projects through the front plate and is considerably extended 10 to afford means for mounting thereon the seconds-hand D' . To the escape-wheel staff there is an independent train, commencing with a wheel c^3 , loose on the shaft c and driven by friction from the back of the pinion C' , as 15 indicated by the tripod-spring c^3 . This is in accordance with my Patent No. 610,229, dated September 6, 1898, and the construction in this respect need not be further described. The shaft b penetrates the front plate A and just 20 forward thereof is reduced and squared at b' and receives on said squared portion the cupped disk E , which has a square aperture to fit the shaft at that point, and on the staff b , forward of the cupped disk E , there is lodged 25 a sleeve G , which is squared at the forward end to receive the minute-hand. This sleeve has at the rear end the disk G' , adapted to enter the cupped disk E , the former being interiorly and the latter exteriorly very slightly 30 tapered to permit the one to enter the other and obtain by slight pressure firm frictional engagement for the work to be done, equivalent to a positive attachment of the two parts to each other. To render this substantially 35 positive connection more certainly positive, the periphery of the disk G' and the inner wall of the flange of the cupped disk E are finely corrugated or serrated, so that when the disk is entered into the cup the engagement 40 is perfectly positive and rigid. The number of corrugations or serrations is equal to or an exact multiple of the number of teeth on the gear-wheel B , so that the hands can be set in correct position whatever teeth of 45 said wheel is meshed with the pinion C' at the synchronizing position of said pinion. The forward end of staff b is threaded, and a thumb-nut G^2 thereon operates to force the sleeve G back on the staff and sink the disk 50 G' in the cupped disk E , thus forcing and retaining the two parts of the clutch which these two disks constitute in engagement. I do not limit myself to the serrations described as the means of engagement between the two 55 parts of the clutch, since obviously this expedient is only superior for certainty and rigidity of engagement to that which would be effected by mere friction between the two slightly-tapered elements; but if such serrations are employed it is important that their 60 number should be as described—to wit, equal to or a multiple of the number of the teeth on the gear-wheel which carries the staff, so that there shall be as many different positions 65 possible in the relative adjustment of the two clutch elements as would be possible by

shifting the mesh of said staff-carrying wheel with the next preceding pinion.

The first wheel K of the train connecting the minute and hour hands is rigid with the sleeve G at the rear portion of said sleeve immediately forward of the clutch-disk G' , so that the hour-hand is set with the minute-hand, the proper relation of the two hands being preserved as is usual in any setting action. The diameter of the disk G' is sufficient to cause the disk to lap behind the intermeshing teeth of the gear K and next wheel K' of the hands-train. This prevents any danger of throwing the gear K out of mesh with the gear K' when the sleeve is moved forward to release the clutch. This construction has a value independent of the synchronizing or automatic setting of the hands by a synchronizing device, for it dispenses 85 with the necessity for the customary means of permitting the hands to be set at will—that is, the frictional connection between the minute-hand staff and the remainder of the motor-train, for with the construction 90 above described while the hands are at all times positively driven, yet by slackening the nut and drawing forward the minute-hand and its sleeve to disengage the two parts of the clutch the entire hands-train commencing with the wheel K on the sleeve G is freed from the anterior driving-train and the hands may be set at will, preserving their proper relations through the train which connects them, and then by pushing back the hand and its sleeve and applying the thumb-nut 100 the clutch again operates to hold the hands as set with respect to the remainder of the train.

L is the synchronizing-electromagnet. L' 105 is its armature carried on the lever M , which extends across the shaft c above the path or orbit of the crank-wrist c^2 , so that when the magnet is energized the armature-lever strikes across the axis of the said shaft in the plane of the orbit of the wrist and encounters the latter wherever it stands, and if it is out of its proper position—that is, the position it would occupy if the clock was running accurately and indicating the exact time at the synchronizing instant, said position being the lowest position in its orbit—it will be forced to that position unless it is almost diametrically opposite the same. The practical range of adjustment which may be 110 caused by the stroke of the lever upon the wrist is about thirty-six degrees less than one-half revolution, and since in the train, as shown in drawings, one revolution of the shaft c occupies seven and one-half minutes 115 one-half revolution less thirty-six degrees corresponds to three minutes, so that correction can be made of an error amounting to three minutes, either slow or fast.

When synchronizing action is performed 120 upon a shaft intermediate the minute and seconds hand staffs, as in the construc-

- tion illustrated, in order that both hands may be rigidly secured to their staffs, respectively, the same or equivalent provision should be made for adjusting the seconds-hand on its staff as that above described with respect to the minute-hand. This is not so essential, however, as in respect to the minute-hand, because the carrying-wheel of its staff being a pinion with only twelve teeth it is not a difficult matter to take note of the position of the hand when assembling the train or to readjust the meshes of this pinion with the next preceding wheel. However, for the purpose of rendering the seconds-hand adjustable with the same effect as above described I provide it with a two-part clutch device. The seconds-hand has its sleeve, which is split to adapt it to hold strongly by friction on its staff, expanded at the rear end to increase its periphery and provided at such increased periphery with twelve notches to correspond with the twelve teeth of its carrying-pinion, and through the staff d^10 a little forward of the front plate I set a transverse pin d^{10} , which is adapted to engage any two notches on sleeve. The frictional grasp of the split sleeve on the pin is sufficient to prevent its longitudinal displacement by accident, and so long as there is no longitudinal displacement the pin lodged in the notches effects a secure positive engagement of the hand with the staff after the movement is fully assembled, the synchronizing stroke being given and both hands then being set at the zero-point of their respective dials.
- I claim—
1. In a clock a gear-frame and train therein connecting positively the minute and seconds hand staffs; synchronizing means operating on the shaft of the train to set both hands at one operation, said hands being rigidly secured to their respective shafts; the means of securing one of the hands consisting of a two-part clutch, having one part rigid with the hand, and the counterpart rigid with the staff, said part and counterpart being adapted to be disengageably engaged positively, as distinguished from yieldingly, against relative rotation at as many different relative positions as there are teeth on the gear-wheel which carries said staff, and means accessible for operation outside the frame for effecting such engagement and disengagement at will.
  2. In a clock, a gear-frame and train therein, a hand-staff, which said train drives positively; a synchronizing-lever and a shaft in said train on which said lever acts to rotate it to certain position; a hand adapted to be rigid with the hand-staff, and means for disengageably securing the hand to the staff, comprising a two-part clutch, whose parts are adapted to be engaged positively, as distinguished from yieldingly, at as many relative positions as there are teeth on the gear-wheel which carries said staff, means connected with one of said parts accessible outside the frame for effecting the engagement and disengagement of said clutch parts.
  3. In a clock, a gear-train, two hand-staffs which said train drives positively, a synchronizing-lever and a shaft in the train intermediate said hand-staffs on which said lever acts to rotate it to a certain position, the hands being adapted to be rigid with their staffs respectively, the means for making them rigid being a two-part clutch, one part being rigid with the hand and the other with the staff, and disengageably engageable positively, as distinguished from yieldingly, at as many different positions as there are teeth on the staff-carrying wheel.
  4. In a clock-train, the minute-hand staff, the minute-hand, a two-part clutch device for making the hand rigid with the staff, one part of the clutch being rigid with the staff, the other part having a sleeve by which it is mounted loose on the staff, and which at the forward end carries the hand rigidly, the staff projecting from the forward end of the sleeve and means for positively forcing and holding the sleeve back to effect unyielding engagement of the clutch and the hands-train having its first wheel rigid with said sleeve forward of the clutch-disk.
  5. In a clock, a gear-frame and train therein connecting positively the minute and seconds hands staffs; synchronizing means operating on a shaft of the train to set both hands at one operation, said hands being secured rigidly to their respective staffs, the means for securing one of the hands being a two-part clutch consisting of a cupped disk rigid with one of said elements and a slightly-tapered disk rigid with the other element and adapted to enter the cupped disk, the part rigid with the hand being movable on the hand-staff to become engaged with and released from the other part; and means accessible outside the frame for moving said movable part into engagement with the other part of the clutch and for holding it unyieldingly in such engagement.
  6. In a clock, a gear-frame and train therein; a hand-staff which said train drives positively; a synchronizing-lever, and a shaft in said train on which said lever acts to rotate it to a certain position; a hand adapted to be rigid with the hand-staff; and means for disengageably securing said hand and staff together consisting of a two-part clutch composed of a cupped disk rigid with one of said elements, and a slightly-tapered disk rigid with the other element adapted to enter the cupped disk, the part rigid with the hand being movable on the hands-staff to become engaged with and released from the other part; and means accessible outside the frame for moving said movable part into engagement with the other part of the clutch and for holding it unyieldingly in such engagement.
  7. In a clock, a gear-train a hand-staff which

- said train drives positively; a synchronizing-lever, and a shaft in said train on which said lever acts to rotate it to a certain position; a hand adapted to be rigid with the hand-staff; and means for disengageably securing such hand to the staff consisting of a two-part clutch comprising a cupped disk rigid with one of said elements and a slightly-tapered disk rigid with the other element adapted to enter the cupped disk, the part rigid with the hand being movable on the hand-staff to become engaged with and released from the other part; and a nut on the forward end of the hand-staff for forcing the two parts of the clutch into engagement.
8. In a clock, a gear-train, and a hand-staff which said train drives positively; a synchronizing-lever, and a shaft in said train on which said lever acts to rotate it to a certain position; a hand adapted to be rigid with the hand-staff; means for disengageably securing such hand to the staff consisting of a two-part clutch comprising a cupped disk rigid with one of said elements and a slightly-tapered disk rigid with the other element adapted to enter the cupped disk, the part rigid with the hand being movable on the hand-staff to become engaged with and released from the other part, the periphery of the other disk and the inner surface of the cupped disk being corrugated or serrated, the number of corrugations or serrations corresponding to the number of teeth on the staff-carrying gear; and means for positively forcing said serrated or corrugated disks into unyielding engagement.
9. A clock-train having one of its shafts cranked between its bearings; an electromagnet on the clock-frame and its armature, a lever on which said armature is carried, extending across the cranked shaft in the plane of the orbit of the crank-wrist, whereby when the magnet is energized said lever may drive the crank-wrist to a point of its orbit most remote in the direction of the movement of the lever.
10. In a clock-train in connection with the minute-hand staff and the seconds-hand staff, a gear-train positively connecting said staffs, and frictionally connected with the remainder
- of the train; a shaft in said train intermediate said hand-staffs, having the driving and driven wheels on it connected as by a crank-wrist or post eccentric to the shaft; the shaft being interrupted at the plane of the orbit of such eccentric post or wrist; a synchronizing electric magnet and its armature, and a lever operated by the armature extending across the axis of the shaft and having a range of movement caused by the armature from one side to the other of said axis at the plane of the orbit of the wrist.
11. In a clock-train in combination with a minute-hand staff and a seconds-hand staff and gear-train positively connecting said staffs and frictionally connected with the remainder of the train, a shaft in said train intermediate said hand-staffs having rigid with it between its bearings an eccentrically-located abutment, or crank-pin, a synchronizing-lever extending across the shaft in the plane of the orbit of the abutment, and means for operating said synchronizing-lever to cause it to encounter said abutment and carry its face which makes said encounter past the axis of the shaft.
12. In a clock-train in combination with a minute-hand staff and a seconds-hand staff and gear-train positively connecting said staffs and frictionally connected with the remainder of the train, a shaft in said train intermediate said hand-staffs having the driving and driven wheels on it connected by a crank-wrist, or post eccentric to the shaft, the shaft being interrupted at the plane of the orbit of such eccentric post or wrist, a synchronizing-lever extending across the axis of the shaft and having a range of movement from one side to the other of said axis at the plane of the orbit of the wrist, and means for operating said lever.

In testimony whereof I have hereunto set my hand, in the presence of two witnesses, at Chicago, Illinois, this 14th day of September, 1901.

CHARLES M. CROOK.
